UNITED STATES PATENT OFFICE.

RAGNAR LARSON, OF CHICAGO, ILLINOIS.

DESIGN FOR A BOY'S WAGON.

55,060.

Specification for Design.

Patented May 4, 1920.

Application filed June 11, 1919. Serial No. 303,488. Term of patent 14 years.

To all whom it may concern:

Be it known that I, RAGNAR LARSON, a citizen of the United States, residing at Chicago, in the county of Cook and State of Illinois, have invented a new, original, and ornamental Design for Boys' Wagons, of which the following is a specification, reference being had to the accompanying drawing, in which the figure is a perspective view of a boy's wagon, showing my new design.

I claim:—

The ornamental design for a boy's wagon, as shown.

In testimony whereof I affix my signature.

RAGNAR LARSON.
